US0D1105820S

(12) **United States Design Patent** (10) **Patent No.:** **US D1,105,820 S**
(45) **Date of Patent:** **** Dec. 16, 2025**

(54) **SHELF**

(71) Applicant: **Lynne Anthony-Campbell**, Corona del Mar, CA (US)

(72) Inventor: **Lynne Anthony-Campbell**, Corona del Mar, CA (US)

(**) Term: **15 Years**

(21) Appl. No.: **29/892,621**

(22) Filed: **May 19, 2023**

(51) **LOC (15) Cl.** **06-04**

(52) **U.S. Cl.**

USPC **D6/680**

(58) **Field of Classification Search**

USPC D6/403, 513, 514, 556, 677, 680, 682, D6/682.1, 682.2, 683, 683.1; D7/601, D7/620, 637, 698, 701

CPC . A47B 87/0269; A47B 87/0276; A47B 43/00; A47B 46/00; A47F 5/05
